UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed October 2, 1922. Serial No. 591,774.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to typewriters, and 10 more particularly to typewriters wherein provision is made for positioning a plurality of work-sheets in the machine, side by side, independently of each other.

A feature of the invention is the provision, 15 in combination, of two collating tables above the platen, at the front thereof, for positioning work-sheets side by side, clamping means co-operating with one of the tables to clamp a sheet, and feed-rollers for co-operating with the platen to feed a sheet 20 on the other collating table only.

Another feature of the invention is the provision, in combination, of two separate means for gaging two work-sheets in the 25 machine side by side, means for feeding one of the work-sheets only, and tally-strip mechanism for feeding a tally-strip around the platen, beneath the inner margins of both sheets, in position to receive certain of 30 the items typed on each of the sheets.

Other features and advantages will hereinafter appear.

In the accompanying drawings,

Figure 1 is a front elevation of the platen-frame of an Underwood standard typewriter, having the feed-rollers omitted at the right side of the platen and having the improvements of the present invention combined therewith.

Figure 2 is a vertical section taken beyond the right end of the platen and looking toward the left in Figure 1.

A platen-frame 10 supports a platen-shaft 11 which carries a platen 12, and is revolvable by the usual Underwood line-spacing mechanism, not shown, operating through a ratchet-wheel 13, or by a knob 14. Feed-rollers 15 of the usual construction are provided to co-operate with the platen at the left side thereof to control the paper and are movable to effective and ineffective positions by the usual paper-release handle 16 and its connected train of mechanism comprising a

shaft 17, crank-arm 18, link 19, crank-arm 20, cam-shaft 21 and the downwardly-extending tails 22 of the levers 23 which carry the feed-rollers. It will be observed that there are no feed-rollers at the right side of the platen (see Figure 1). A bracket 24 is secured upon the platen-frame 10 and supports collating tables 25 and 26, side by side, above the platen, at the front thereof. The table 25 has lateral edge gages 27 and 28, and the table 26 has lateral edge gages 29 and 30 for assisting in positioning the work-sheets in the machine. A plate 31 fixed upon the outer face of the edge gage 27 has outwardly-bent ears 32 with holes therein which serve as bearings for a shaft 33 having a crank-handle 34 and a clamping arm 35 fixed upon it. A coil spring 36 is connected to pins 37 and 38 on the clamping arm 35 and one of the ears 32, respectively, the arrangement being such that the spring will cross the center of the shaft 33 when the clamping arm is moved in either direction between effective and ineffective positions, and will therefore serve to hold the clamping arm in either of these positions.

Tally-strip mechanism comprising reels 39 and 40 is provided for feeding a tally-strip 41 around the platen in a position to underlie a portion of each of the sheets on the collating tables 25 and 26, so that it will receive impressions of the items typed on these portions of the sheets. This tally-strip mechanism is identical with that disclosed in the patent to Hart, No. 1,281,160, and will not, therefore, be described further.

Public utility companies, such as electric light companies, which operate over a large territory and have branches at different localities, sometimes maintain two different kinds of ledgers, one known as a location ledger which always stays at a particular location, and the other known as a customer's ledger which follows the customer as he moves from place to place in the territory served by the company. At the time a bill is rendered to a customer entries are made in appropriately headed columns of a location ledger-sheet indicating the date, meter readings, consumption, several items of charge and the total amount of the bill. At the same time the date and total amount of

the bill are entered in date and debit columns at the left of the customer's ledger-sheet. The machine disclosed is used for doing this work as follows: with the feed-rollers thrown off, the location ledger-sheet 42 is inserted at the left side of the platen and adjusted to proper position. The feed-rollers are then moved to effective positions. The customer's ledger-sheet 43 is then inserted in the machine at the right side of the platen, where there are no feed-rollers, and adjusted to proper position. The clamp is moved to effective position to hold the customer's ledger-sheet, and a single line of items is written on the sheets. The clamp and feed-rolls are then released, and both ledger-sheets are removed from the machine. The tally-strip lies in position to receive the item of consumption and the various items of charge including the total amount of the bill from the location ledger-sheet, and extends to the right far enough to receive the date and the total amount of the bill from the customer's ledger-sheet. The total amount of the bill, therefore, appears on the tally-strip as it has been written on each of the ledger-sheets. The strip is then fed a line-space distance as a final operation. It will be seen that the tally-strip affords a convenient check to ascertain whether or not the same amount has been written upon the two ledger-sheets after they have been separated. The above example should, of course, be regarded merely as illustrative of the use of the invention, and not as defining the scope of the use to which the invention may be put, as for example:—

The mechanism shown and described provides for two distinct modes of operation, namely, the rollers 15 may be considered as clamping elements to hold the adjusted sheet 42 during a single-line entry, and the rollers cast off prior to the removal of the sheet from the platen, and the tally-strip line-spaced after the sheet has been removed; or the rollers may serve as paper-feeding elements to simultaneously feed the work-sheet and the underlying tally-strip in unison, where the nature of the typing requires two or more single-line entries on one of the work-sheets, in which case the sheet and the underlying tally-strip would be line-spaced in unison after each line entry. The sheet adjusted at the right hand of the platen and clamped to the collating table would not be typed until the last entry on the companion sheet had been concluded and a debit or a credit total rendered; after which operation, the total and any other data would be entered upon the right-hand sheet, in a single-line entry, and both sheets then removed from the platen. With this latter method, it will be noted that three work-sheets are employed at each typing operation, compris-

ing one stationary sheet and two sheets having means for a joint line-feeding movement with the platen, through the manipulation of the usual Underwood line-spacing mechanism.

Variations may be resorted to within the scope of the invention, and portions of the improvements may be used without others.

Having thus described my invention, I claim:

1. In a typewriting machine, a platen, collating means for guiding two sheets in the machine, side by side, feed-rollers co-operating with the platen to feed one of the sheets without affecting the other, and a clamp for co-operating with the collating means to clamp the second sheet.

2. In a typewriting machine, means for guiding a work-sheet by both lateral edges, feeding mechanism for feeding the work-sheet, means for guiding a second work-sheet by both lateral edges beside the first work-sheet, and for clamping it in a desired position, the feeding mechanism being inoperative to act upon the second work-sheet, and tally-strip mechanism arranged to feed a tally-sheet beneath the adjacent margins of the work-sheets.

3. In a typewriting machine, means for guiding a work-sheet by both lateral edges, feeding mechanism for feeding the work-sheet, means for guiding a second work-sheet by both lateral edges beside the first work-sheet, the feeding mechanism being inoperative to act upon the second work-sheet, and tally-strip mechanism arranged to feed a tally-sheet beneath the adjacent margins of the work-sheets.

4. In a typewriting machine, means for guiding a work-sheet, feeding mechanism for feeding the work-sheet, means for guiding a second work-sheet beside the first work-sheet, and for clamping it in a desired position, the feeding mechanism being inoperative to act upon the second work-sheet, and tally-strip mechanism arranged to feed a tally-sheet beneath the adjacent margins of the work-sheets.

5. In a typewriting machine, a platen, means for guiding two sheets, side by side, feed-rollers for clamping only one of the sheets against the platen, a clamp for clamping the other sheet independently of the platen, and tally-strip mechanism for feeding a tally-strip beneath a portion of each of the sheets.

6. In a typewriting machine, a platen, means for guiding two sheets, side by side, independently of each other, means for clamping one of the sheets to the platen independently of the other, additional means for clamping said other sheet, and tally-strip mechanism for feeding a tally-strip beneath a portion of each of the sheets.

7. In a typewriting machine, a unitary

- platen, means for guiding two sheets, side by side, around the platen, feed-roller mechanism comprising feed-rollers for co-operating with the platen, at one side thereof, to grip and feed one of the sheets without affecting the other, so that the second sheet can be inserted and adjusted with the feed-rollers effective, means for clamping the second sheet to fix its position, and tally-strip mechanism for feeding a tally-strip around the platen beneath both sheets. 8. In a typewriting machine, the combination with a traveling carriage and a platen therein, of a plurality of collating tables arranged side by side above the platen at the delivery side thereof to collate work-sheets side by side upon the platen in non-overlapping relation, a common support for the two collating tables, a clamp mounted on one of them to co-operate with it in clamping a work-sheet, and means for quickly attaching the support of the collating tables to the carriage. 9. In a typewriting machine, a platen, a pair of work sheets, rollers cooperating with the platen to feed one work-sheet, means for guiding both work-sheets through the machine side by side in non-overlapping relation, comprising edge gages for the right and left edges of each sheet, and a clamp to hold one sheet stationary during the feeding of the other sheet. 10. In a typewriting machine, a platen, means for guiding a pair of work-sheets around the platen side by side in non-overlapping relation, comprising side-edge gages for each work-sheet, a tally-strip partially underlying each work-sheet, and means co-operating with the platen to feed one work-sheet and the tally-strip in unison. 11. In a typewriting machine, a platen, means for guiding a pair of work-sheets around the platen side by side in non-overlapping relation, comprising a collating table carrying side-edge gages for each sheet, a clamp on the collating table to clamp one sheet thereto, and means to feed the other sheet and tally-strip in unison. 12. In a typewriting machine, a platen, means for guiding a pair of work-sheets around the platen side by side in non-overlapping relation, comprising a collating table carrying side-edge gages for each sheet, a clamp on the collating table to clamp one sheet thereto, and a mutilated system of feed-rollers co-operating with the platen to feed one work-sheet and the tally-strip in unison. 40 45 50 55
